UNITED STATES PATENT OFFICE.

JOHN BARRETTE DOYLE, OF HAMBURG, MISSISSIPPI.

AIR-COCK OPERATOR.

1,142,683.

Specification of Letters Patent.

Patented June 8, 1915.

Application filed September 1, 1914. Serial No. 859,587.

To all whom it may concern:

Be it known that I, JOHN B. DOYLE, a citizen of the United States, and a resident of Hamburg, in the county of Franklin and 5 State of Mississippi, have invented certain new and useful Improvements in Air-Cock Operators, of which the following is a specification.

My invention relates to air-brake systems 10 of railway cars, particularly to freight cars, and specifically to the air-cocks, at the ends of such cars, which are adapted to be opened when two cars are coupled together and closed when said cars are uncoupled, and the 15 main object of the invention is to provide means for accomplishing these operations from a position of safety, on the sides of the cars.

A further object is to so construct the said 20 actuating means as to be readily extended to any desired operating point or points.

A further object is to provide means for automatically holding the air-cocks and operating means in any adjusted position.

25 A further object is to so connect the said operating means with the air-cocks as to permit the normal actuation thereof.

A further object is to provide, in connection with such operating means, an extensible member which admits of connection with an air-cock and the body of a car at the most convenient points; and further objects are to provide such devices which are simple in construction and in installation, positive in 35 action, capable of considerable latitude in installation, and comparatively inexpensive.

My invention is fully described in the following specification, of which the accompanying drawings form a part, in which like 40 parts are designated by like reference characters in each of the views, and in which:—

Figure 1 is a perspective view of the end of a railway car provided with my invention, according to one method of installation; Fig. 2 is an enlarged, fragmentary, view of the connection with an air-cock, partly in section; Fig. 3 is a sectional, detached, view of a detail which I employ; Fig. 4 is an enlarged, perspective, view of 50 another detail; Fig. 5 is a similar view of still another detail; and Fig. 6 is an end view of a car provided with my invention according to another method.

In Figs. 1 and 6 of the drawings I have

illustrated a portion 7 of a railway car, having the draw-head 8, the fixed tubing 9 of the air-brake system, the flexible hose 10 for car connection, and the air-cock 11 controlling the passage of air through said hose, and I also illustrate the means 12 for drawing the coupling pin of the draw-heads of two cars.

As shown in Fig. 2, the stem 13 of the air-cock 11 extends above the usual handle 14, or is so extended if not so formed originally, 65 and the extended end is of angular form as shown at 15 and is provided with a transverse bore 16.

Seated on the stem 13 is an angularly socketed sleeve 17, held by means of a pin 70 18, and the upper end of which is yoke-shaped at 19 to form, with the cross shafts 20 and yoke 21 on the rod 22, a universal joint, and said rod 22 is connected, by means of a universal joint 23, with an inclined rod 75 24, in turn connected, by means of a universal joint 25, with a horizontally arranged rod 26 rotatable in cleats 27 secured to the body of the car; the rod 26 is in turn connected, by means of a universal joint 28, 80 with an inclined rod 29 in turn connected, by means of a universal joint 30, with a vertical rod 31 rotatable in cleats 32, Fig. 6, and provided with a handle 33 at its lower end whereby the rod 26 may be rotated, and 85 thus the sleeve 17 and air-cock stem 13, in either direction.

In Fig. 1 the rod 31 is arranged close to the draw-head, but on the side opposite the position of the air-cock 11, in order to allow 90 a trainman to actuate said air-cock without the necessity for reaching over the draw-head, this having resulted in many accidents, whereas in Fig. 6 the rod 31 is arranged close to the side of the car, whereby 95 the trainman is not required to enter between cars to actuate the air-cock when they approach each other for coupling, the latter arrangement requiring that the rod 26 be longer than in the former arrangement. 100

In Fig. 1 I have shown two additional operating handles 34 and 35, one at each side of the car, the former being secured to a vertical rod 36 rotatable in cleats 37 and joined, by means of a universal joint 38, 105 with a rod 39 in turn joined, by means of a universal joint 40, with a horizontal rod 41 rotatable in cleats 42, and the rod 41 is

locked to the rod 26 by means of a bridge 43 of such dimensions as to permit free operation of the universal joint 25, and it will be seen that, if the handle 34 be revolved, the 5 rod 26 is rotated accordingly, as is also the sleeve 17 and stem 13 of the air-cock.

The handle 35 is secured to a vertical rod 44 rotatable in cleats 45 and joined, by means of a universal joint 46, with a rod 47 in turn 10 joined, by means of a universal joint 48, with a horizontal rod 49 rotatable in cleats 50 and secured to the rod 26 by means of a bridge 51 in all respects similar to the bridge 43, and it will be seen that actuation of the 15 handle 35 also rotates the air-cock stem correspondingly.

In the arrangement illustrated in Fig. 1 three operating handles, 33, 34, and 35, are provided, but either 33 or 35 may be dispensed with, if desired, together with the connected parts, all of said handles being illustrated in order to demonstrate the adaptability of my invention to meet different conditions, as I do not limit myself 25 to any specific arrangement nor handle position, as the varying conditions met with may require certain modifications over the forms shown and described.

As clearly illustrated in Figs. 1, 5, and 30 6, I may bend any of the rods which are arranged close to the car body, but preferably the horizontally arranged rods, to form a loop 52 of relatively short radius, and over which bears a plate spring 53 secured to the body of the car, the function 35 of said loop and spring being to hold the device, as a whole, in either adjusted position, and thereby lock the air-cock in adjusted position, but I do not limit myself 40 to the use thereof.

If the arrangement of the operating means for the coupling pin is such as to render the sleeve 17 and connections too short, I may provide a telescopic construction 45 of the rod 22, as shown in Fig. 3, two members 54 and 55 telescoping one within another and each of which carries the corresponding portion of the adjacent universal joint, and the movement of said members is limited by means of pins 56 slidable in 50 slots 57.

It will thus be seen that I provide what may be termed an elastic combination of articulated elements in operative connection 55 with the air-cock 11, and adapted to be operated from a desired point or from any one of a plurality of desired points; the device is applicable to a car without any alteration in the latter; the inclined, articulated, 60 elements permitting the elements on the car body to be in a different vertical plane than that of the air-cock; and it will be understood that I may make changes in and modifications over the details shown and described, within the scope of the following 65

claims, without departing from the spirit of my invention, or sacrificing its advantages.

Having fully described my invention, what I claim as new, and desire to secure 70 by Letters Patent, is:—

1. In combination with a railway car provided with an air-brake system having an air-cock arranged at the end of said car; a socketed sleeve engaging said cock, a vertical rod, a universal joint connecting said sleeve and vertical rod, an inclined rod, a universal joint connecting said vertical and inclined rods, a horizontal rod carried by 75 said car, a universal joint connecting said inclined and horizontal rods, and means for rotating said horizontal rod and thereby said air-cock.

2. In combination with a railway car provided with an air-brake system having an air-cock arranged at the end of said car; a socketed sleeve engaging said cock, a vertical rod, a universal joint connecting said sleeve and vertical rod, an inclined rod, a universal joint connecting said vertical and inclined rods, a horizontal rod carried by 80 said car, a universal joint connecting said inclined and horizontal rods, an inclined rod on said car, a vertical rod on said car, universal joints connecting said vertical and 85 inclined rods and said inclined and horizontal rods, and a handle on said last named vertical rod to actuate said air-cock.

3. In combination with a railway car provided with an air-brake system having an air-cock arranged at the end of said car; a socketed sleeve engaging said cock, a vertical rod, an inclined rod, a horizontal rod carried by the car, universal joints between 90 said vertical and inclined rods and between 95 said inclined and horizontal rods, a handle on said car, a vertical rod on said car, universal joints connecting said vertical and inclined rods and said inclined and horizontal rods, and a handle on said last named vertical rod to actuate said air-cock.

4. In combination with a railway car provided with an air-brake system having an air-cock arranged at the end of said car; a socketed sleeve engaging said cock, a vertical rod, an inclined rod, a horizontal rod carried by 100 said car, universal joints connecting said vertical and inclined rods and between 105 said inclined and horizontal rods, a handle connected with said horizontal rod to rotate the same to actuate said cock, and means for locking said horizontal rod in desired position.

4. In combination with a railway car provided with an air-brake system having an air-cock arranged at the end of said car; a socketed sleeve engaging said cock, a vertical rod, an inclined rod, a horizontal rod carried by 110 said car, universal joints connecting said vertical and inclined rods and said inclined and horizontal rods, a handle connected with said horizontal rod, a supplemental horizontal rod carried by 115 said car, a bridge spanning the joint between said inclined and first named horizontal rods and connecting said horizontal rods together, and a handle on said supplemental horizontal rod.

5. In combination with a railway car provided with an air-brake system having an air-cock arranged at the end of said car; a socketed sleeve engaging said cock, a vertical rod, an inclined rod, a horizontal rod 120 carried by said car, universal joints connecting said vertical and inclined rods and said inclined and horizontal rods, a handle connected with said horizontal rod, a supplemental horizontal rod carried by 125 said car, a bridge spanning the joint between said inclined and first named horizontal rods and connecting said horizontal rods together, and a handle on said supplemental horizontal rod.

6. In combination with a railway car provided with an air-brake system having an air-cock arranged at the end of said car; a socketed sleeve engaging said cock, a vertical rod, an inclined rod, a horizontal rod 130 carried by said car, universal joints connecting said vertical and inclined rods and said inclined and horizontal rods, a handle connected with said horizontal rod, a supplemental horizontal rod carried by said car, a bridge spanning the joint between said inclined and first named horizontal rods and connecting said horizontal rods together, and a handle on said supplemental horizontal rod.

carried by said car, universal joints connecting said vertical and inclined rods and said inclined and horizontal rods, a handle at each side of said car connected with said 5 horizontal rod to actuate said cock, and means for locking said horizontal rod in desired position.

In testimony whereof I have signed my name to this specification in the presence of two subscribing witnesses.

JOHN BARRETTE DOYLE.
